US00D932469S

(12) **United States Design Patent** (10) **Patent No.:** **US D932,469 S**
(45) **Date of Patent:** **** Oct. 5, 2021**

(54) **WIRELESS EARBUD**

(71) Applicant: **LG Electronics Inc.**, Seoul (KR)

(72) Inventors: **Byunghyun Yi**, Seoul (KR); **Soonhyun Park**, Seoul (KR); **Gayeong Lee**, Seoul (KR)

(73) Assignee: **LG ELECTRONICS INC.**, Seoul (KR)

(**) Term: **15 Years**

(21) Appl. No.: **35/509,560**

(22) Filed: **Dec. 11, 2019**

(80) **Hague Agreement Data**

Int. Filing Date: **Dec. 11, 2019**

Int. Reg. No.: **DM/205690**

Int. Reg. Date: **Dec. 11, 2019**

Int. Reg. Pub. Date: **Jun. 12, 2020**

(30) **Foreign Application Priority Data**

Jun. 11, 2019 (KR) 30-2019-0027671

(51) **LOC (13) Cl.** **14-01**

(57) **CLAIM**

The ornamental design for a wireless earbud, as shown and described.

DESCRIPTION

1. Wireless earbud

1.1 : Perspective

1.2 : Front

1.3 : Back

1.4 : Left

1.5 : Right

1.6 : Top

1.7 : Bottom

The broken lines depict portions of wireless earbud that form no part of the claimed design; reproduction 1.1 is a front perspective view of the wireless earbud; reproduction 1.2 is a front view thereof; reproduction 1.3 is a back view thereof; reproduction 1.4 a left side view thereof; reproduction 1.5 is a right side view thereof; reproduction 1.6 is a top plan view thereof; reproduction 1.7 is a bottom plan view thereof; Present design is a right wireless earbud; the left earbud is a mirror image thereof.

1 Claim, 7 Drawing Sheets
